UNITED STATES PATENT OFFICE.

PAUL M. MOHLER AND SYLVESTER J. FRY, OF ROCKAWAY, OREGON.

CARBURETING APPARATUS.

1,121,651.

Specification of Letters Patent. Patented Dec. 22, 1914.

Application filed December 29, 1913. Serial No. 809,355.

To all whom it may concern:

Be it known that we, PAUL M. MOHLER and SYLVESTER J. FRY, citizens of the United States, residing at Rockaway, in the county 5 of Tillamook, State of Oregon, have invented a new and useful Carbureting Apparatus, of which the following is a specification.

The present invention relates to improvements in carbureting apparatus, one object 10 of the invention being the provision of means which after the explosion engine has attained a certain speed, will supply the carbureted air by means of a fan or other 15 means, thus relieving the engine or the piston thereof, from the extra work of sucking the charge into the explosion chamber, and at the same time insuring a better mixture when the same has entered the explosion 20 chamber.

A further object of the present invention, is the provision of a mechanism adapted to be connected to a liquid fuel spraying chamber, in which is mounted a valve controlled 25 fuel inlet actuated due to the suction effect thereon, to supply the fuel in the proper quantity according to the speed of the engine, the mechanism for producing such suction also constituting a mixing means 30 for thoroughly commingling the fuel and air to produce the carbureted air before the discharge or forcing thereof through the intake manifold to the engine.

With the foregoing and other objects in 35 view which will appear as the description proceeds, the invention resides in the combination and arrangement of parts and in the details of construction hereinafter described and claimed, it being understood 40 that changes in the precise embodiment of the invention herein disclosed can be made within the scope of what is claimed without departing from the spirit of the invention.

In the drawings Figure 1 is a sectional 45 view through the complete apparatus, showing the parts in the position they assume when under normal running conditions. Fig. 2 is a section on an enlarged scale taken on line 2-2 of Fig. 1. Fig. 3 is a 50 cross sectional view through the fan chamber showing the relative positions of the parts. Fig. 4 is a perspective view taken from the inner face of the valve carrying member of the fan. Fig. 5 is a perspective 55 view of the valve. Figs. 6 and 7 are detail

views of the fuel portage controlling and adjustable valves.

Referring to the drawings, the numeral 1 designates a valved conduit for supplying gasolene, the primary charging fuel, and 2 60 a valved conduit for supplying kerosene or a less volatile fuel. The valved conduit 2 is connected to the pipe 3, whose lower end 4 is provided with a port 5 controlled by a cone valve 6. This cone valve 6 is connected to a frame or yoke 7 connected upon the inner side of the diaphragm 8 which is attached to the mixing chamber 9 of the present mechanism. A frame 10 is carried by the chamber 9 astride or above the dia- 70 phragm 8, and has disposed therein for adjustment, the headed screw 11, which maintains the spring 12 at the desired adjustment so that the diaphragm may be permitted the necessary movement when actuated to control the valve 6 and thus permit the introduction of the liquid fuel into the casing 9, 75 as will presently appear. A port 13 is provided with the conduit 17 and is controlled by the spring closed valve 14. By this 80 means, air may be admitted to such conduit to mix with the inrushing gasolene, from the pipe 1, at its nozzle 1', within the conduit 17. The valve 1^a that controls the nozzle 1', is connected to the valve 14 by 85 means of the plate 1^b, so that when the throttle, as will later appear, permits both valves 14 and 1^a to open to supply the starting charge of carbureted air. In order to heat the chamber 9, the exhaust manifold 15 of 90 the explosion engine is disposed transversely thereof, as clearly illustrated in Figs. 1 and 2. Connected to the conduit 17 and leading thereto, is the fan chamber 19, which as clearly shown is provided with a stuffing 95 box bearing 20 which co-operates with the standard bearing 21 to properly support the shaft 22 which is operated by the pulley 23, and within the casing 19 carries the mixing fan 24. This fan 24 is provided with the 100 collar or sleeve 25, which is adapted to surround the member 26, through which the combined charge of fuel and air is permitted to enter the center of the fan 24 and be directed by the frusto-conical hub 24' 105 thereof in outward directions, so that when the fan 24 is rotated, the carbureted air is thoroughly mixed thereby and directed through the conduit 17 into the intake manifold 18 of an explosive engine (not shown). 110

2
 The pulley 23 is operated from the explosion engine (not shown), and according to the load placed upon the engine, the speed thereof varies. The same if desired, 5 may be connected to a governor, so that the desired speed of the fan as before stated, according to the load of the engine will be maintained and thus the proper charge of carbureted air will be supplied by the fan 10 24 to the engine, without placing the strain of sucking upon the pistons of the engine. The directing member 26 is carried upon the inner face of the detachable portion or wall 27 of the fan casing, while secured to the 15 outer face of such wall is the block 28, which as clearly shown in Fig. 4, is provided with the air intake opening 29 and the fuel intake opening 30. A recess 31 is provided in the inner face of the block 28 and has the projecting rib 32 and the slot 32', the purposes 20 of which will presently appear.

A slide valve 33, as clearly shown in detail in Fig. 5, is disposed for sliding movement within the recess 31 and the adjacent 25 face of the block 27, said valve being provided with the slot 34 which fits astride the rib 32, and thus co-operates therewith to prevent the mixture of the air and gas before the introduction thereof into the directing 30 member 26. The stem 35 of the valve 33 is mounted for sliding movement in the slot 32' of the block 28, and is connected for reciprocatory movement to the link 36, and the bell crank lever 37, said lever 37 being 35 operated by the throttle controlling rod 38. A second bell crank lever 39 is operably connected to the rod 38. The rod 40 is controlled thereby to regulate the distance of movement and also the operation of the 40 valves 1^a and 14, previous to the admission of the kerosene charge from the fan casing 19, the rod 40 being in reality an adjustable stop for disposition adjacent the under side and in the path of the valve 1^a. A port 43' 45 is provided in the casing 19, and has connected thereto, the conduit 44', which leads into the outer face of the block 28 and into the elongated air slot 30, so that the fuel mixed in the chamber 9 will be drawn 50 through the port 43' and conduit 44' and through the port 30 into the mixing chamber 26 to there receive the inrush charge of air through the port 29. The fan 24 in rotating, will therefore thoroughly commingle 55 the air and fuel so as to produce a thoroughly mixed carbureted air, the fan thus causing the thoroughly mixed carbureted air to follow the direction of the arrows as shown in Fig. 1, to consequently be forced 60 into the intake manifold and the explosion chamber of the engine.

The structure herein shown, is so arranged, that when the valve 33 has closed the ports 29 and 30, the valves 1^a and 14 65 will be permitted to open and there will be

communication from the pipe 17 through the intake manifold 18, the valves 1^a and 14 being closed when the engine is running its proper speed and the mixture is being mixed by the fan 24 and entering the casing 70 through the ports 29 and 30 controlled by the valve 33. According to the speed of the engine, the valve 33 is operated to uncover the ports 29 and 30, such ports being constructed so as to provide the proper proportioned mixture of fuel and air when the same is delivered within the fan casing. It will thus be evident that at the initial starting of the engine, the suction of the piston will produce a vacuum effect in the 80 conduit 17 and consequently intermittently actuate the valves 1^a and 14 and permit the spraying or atomizing of the fuel through the port 1' of the pipe 1, there to be mixed with the air inrushing through 85 the port 13 and finally through the intake manifold 18 to the engine. When the engine has maintained the desired speed, the rod 38 will be operated so as to close the valves 1^a and 14 and open the valve 33, thus 90 causing the fuel from the chamber 9 to be directed through the conduit 44', and as the fan 24 is being operated, the suction action thereof will draw the fuel and air into the casing 19 and there intermix the same. 95 As the engine speeds, the fan 24 will be operated proportionately, and the throttle rod 38 will also be operated proportionately to open the valve 33 and thus permit of the introduction of a greater charge of fuel and air for supplying the motor. At the same time, the action of the fan through the conduit 4 will tend to vibrate the diaphragm 8, or maintain the same in such position, that the valve 6 will permit the opening 100 of the port 5 and consequently the atomization of the fuel within the chamber 9. By means of the exhaust pipe 15, it is evident that the chamber 9 will be heated, such heat assisting in the vaporization of the fuel 105 before the introduction thereof through the pipe 44. By this construction, it is evident that the primary starting of the engine may be done by the employment of gasoline through the valved pipe 1, after which 110 the valved pipe 1 is cut off and the valved pipe 2 is open so as to permit the introduction of kerosene, which due to the heating of the chamber 9 will be readily vaporized 115 to produce the desired carbureted air for delivery to the engine. The block 28 is recessed as at 45 to receive the plate valve 46, which by reason of the threaded bore 47 and the elongated slot 48, and an adjusting screw (not shown) may be adjusted to vary 120 the size of the port 30, for use with various fuels.

What is claimed is:

1. A carbureting apparatus, including a casing, a fuel supply pipe leading thereinto, 130

- 1 a diaphragm actuated valve for controlling the supply of fuel from the pipe to the casing, an intake manifold, a rotary carbureted air mixing and supplying device having its outlet connected to the intake manifold, a pipe leading from the casing to said device, and a valve disposed between the said last pipe and the device and having an open air port, whereby the admission of fuel and air to said device is controlled. 40
- 2 2. A carbureting apparatus, including a casing, a fuel supply pipe leading thereto, a diaphragm actuated valve for controlling the supply of fuel from the pipe to the casing, an intake manifold, a rotary carbureted air mixing and supplying device having its outlet connected to the intake manifold, a pipe leading from the casing to said device, a valve disposed between the said last pipe and the device and having an open air port, whereby the admission of fuel and air to said device is controlled, an independent fuel supplying means connected to the device adjacent the intake manifold, and means connected to the latter valve and to the fuel and air controlling valve, whereby the independent valve is cut off and the other valve is opened, or vice versa. 45
- 3 3. A carbureting apparatus, including a casing, a fuel supply pipe leading thereto, a diaphragm actuated valve for controlling the supply of fuel from the pipe to the casing, an intake manifold, a rotary carbureted air mixing and supplying device having its outlet connected to the intake manifold, a pipe leading from the casing to said device, and a valve disposed between the said last pipe and the device and having an open air port, whereby the admission of fuel and air to said device is controlled, said valve including a block attached to said device and having a port therethrough in communication with the outside air and a second port in communication with the conduit and the interior of the device, and a single sliding member mounted in the block for simultaneously controlling both ports. 50
- 4 4. A carbureting apparatus, having a carbureted air mixing and supplying device, comprising a casing having a fuel and air inlet adjacent the center portion thereof and a carbureted air outlet adjacent the periphery thereof, a rotary fan mounted in the casing, and a valve for controlling the admission of fuel and air to the casing, including a block having a port in communication with the outside air and a fuel admitting port, and a plate slidably mounted in said block for simultaneously intersecting said ports to control the admission of fuel and air to the casing. 55
- 5 In testimony that we claim the foregoing as our own, we have hereto affixed our signatures in the presence of two witnesses.
